UNITED STATES PATENT OFFICE.

THEODORE S. BINDSCHEDLER, OF DETROIT, MICHIGAN, ASSIGNOR TO BURROUGHS ADDING MACHINE COMPANY, OF DETROIT, MICHIGAN, A CORPORATION OF MICHIGAN.

TIME SWITCH FOR ADDING MACHINES.

Application filed May 13, 1920. Serial No. 381,086.

To all whom it may concern:

Be it known that I, THEODORE S. BINDSCHEDLER, a citizen of Switzerland, residing at Detroit, in the county of Wayne, State 5 of Michigan, have invented certain new and useful Improvements in Time Switches for Adding Machines, of which the following is a specification.

My invention relates to adding machines 10 driven by continuously rotating motors, a type of which is shown in patent to Vincent, No. 866,750 issued September 24, 1907. In such electric driven adding machines the rock shaft by the operation of which a number set up on the keyboard is carried into the machine is oscillated from a rotary shaft which is given a complete rotation for this purpose whenever the clutch intermediate said shaft and the continuously running 15 electric motor is thrown into engagement after the desired number is set up in the machine, by the depression of its finger-bar. Obviously, it is essential that the motor circuit remain closed as long as the machine is 20 in use and an ordinary switch will serve for this purpose. It frequently happens, however, where a hand-switch is employed that it is inadvertently left in the closed position after the operator has finished using the 25 machine, with the result that there is a considerable waste of current and useless wear upon the motor. Prior to my invention efforts have been made with more or less success to provide a means by which the motor 30 circuit is automatically opened within a definite period after the last number is carried into the machine. An example of such a construction is shown in patent to Rinsche, No. 1,310,965, granted July 22, 1919. In the 35 machine of said Rinsche patent the depression of the finger-bar for closing the clutch to operate the mechanism for carrying the number set up into the machine trips a timing mechanism which, after a desired period 40 opens the motor switch unless in the meantime the finger-bar is again operated to trip said mechanism. The time within which the mechanism opens the switch is controlled by a dash-pot. My invention is in the nature 45 of an improvement upon the time switch disclosed in said Rinsche patent in which the dash-pot is dispensed with and the time switch more certainly and accurately controlled by thermostatic means, thus effecting 50

an increased saving in current consumption 55 and also more completely protecting the motor.

In the accompanying drawings I have shown and in the following specification described in detail a preferred form of my invention. It is to be understood, however, that the specific disclosure is for the purpose 60 of exemplification only and that the scope of the invention is set forth in the following claims in which I have endeavored to distinguish my invention from the prior art 65 so far as known to me without however relinquishing or abandoning any portion or feature thereof.

In the drawings Fig. 1 is a vertical section on an enlarged scale through the casing of a time switch embodying my invention, the switch itself being shown in elevation and in the open position; Fig. 2 an elevation of the switch partly in section, the contacts 70 being shown closed; Fig. 3 a vertical section on a plane parallel to the plane of Figs. 1 and 2; Fig. 4 an enlarged vertical section of the thermostat element partly broken away in the center; Fig. 5 a side elevation at 75 right angles to Figs. 1, 2 and 3 partly in vertical section; Fig. 6 a detail elevation of certain parts from the same point of view as Figs. 1, 2 and 3 but with the parts in 80 different positions; Fig. 7 a horizontal sectional view on the line 7—7 of Fig. 1; Fig. 8 a horizontal section on the line 8—8 of Fig. 1 with parts broken away to more clearly illustrate the construction; Fig. 9 a detail perspective of the thermostat switch; Fig. 10 a wiring diagram of the switch, and 85 Fig. 11 an enlarged vertical section of a detail on the line 11—11 of Fig. 1.

Each part is identified by the same reference character wherever it occurs throughout the several views.

In the preferred form of my invention shown in the drawings and hereinafter described it is applied to a switch of the same character, except as hereinafter specified, as 100 that illustrated in said Rinsche patent and therefor I have deemed it unnecessary to indicate herein the adding machine proper, the motor and the clutch for effecting driving connection between the motor and the mechanism of the adding machine, and in so far 105 as the construction of my present invention is common also to the Rinsche construction

aforesaid, it will be but briefly described as reference may conveniently be made to the aforesaid Rinsche patent for a fuller description thereof.

5 Referring now more particularly to Figs. 1 and 5, 23 indicates the end of a short shaft for controlling the clutch, not shown, and 24 is a mutilated gear thereon which meshes with a similar gear 25 upon an arm 26 which 10 is raised when the finger-bar above mentioned is depressed by the operator. A rod 27 extending through a loop 26^a and more fully shown and described in said Rinsche patent communicates motion from the finger-bar to arm 26. Binding posts 30, 31 are connected by conductors in the cord 29 to a suitable source of current. To the binding post 30 is also secured the end 32 of one of the conductors leading to the motor, the other 15 of which conductor is connected to the binding post 33. The binding posts 31 and 33 are connected respectively to the plate springs 35, 34 of a knife switch, the movable knife 36 of which is carried by but insulated 20 from an arm 37 pivoted upon a stud 38 secured to the casing 39 of the clutch. (See Figs. 1, 5 and 7.) A convenient means for securing the knife upon the lever 37 is a stud 40 projecting from the face of said 25 lever surrounded by an insulating bushing 40^a extending through the knife 36, the stud and bushing projecting through a circular opening in the knife. A plate spring 41 riveted to the lever at 42 holds the knife in 30 place on the stud and bushing, it being understood, of course, that there is suitable insulation 40^b between the lever and spring and said knife. The knife is free to turn within a small angle to accommodate itself 35 to the contact springs. To the arm 37^a of said lever 37 is connected a spring 46 the other end of which is attached to a stud 47 upon the framework so that said spring tends to throw the lever carrying the knife 40 toward the contact springs 34, 35. As seen 45 in Fig. 1, however, the lever 37 is normally held in open position by a latch 48 which engages the shoulder or abutment 49 upon the lever for this purpose. The spring 50 connected to the stud 47 and to the tail of the 50 latch 48 maintains the latter in contact with the shoulder on the lever. The tail 51 of the latch extends into the path of movement of the washer 52 secured to the lower end of the 55 rod 27 heretofore described as constituting a part of the clutch controlling mechanism, so that when said rod is raised by the depression of the finger-bar it engages and trips the latch 48 permitting the lever 37 to be 60 swung by spring 46 to close the switch. The closing of the switch completing the circuit through the motor energizes the latter and it continues in operation until the knife switch is again opened in the manner hereinafter described.

Provision is made for moving the latch to a position in which, (unless it be again tripped by the movement of the bar 27) it will again pick up the lever 37 and restore it to the open position. With this in view said 70 latch is pivoted at 65 upon a T-shaped lever 66 which is likewise fulcrumed upon the stud or post 38; see Figs. 1 and 7. The T-lever is normally maintained in the open position shown in Fig. 1 by a spring 67 secured 75 to the arm 66^a of said lever and to stationary stud 67^a. Movement of the T-lever under the impulse of spring 67 is limited by a latch 72 hereinafter described which, together with the spring normally holds the T-lever 80 in the position shown in Fig. 1 in which the pawl or latch 48 maintains the knife-carrying lever 37 in open position. Latch 72 is pivoted at 73 and capable of a slight oscillation vertically about said pivot, and its lower 85 edge is of irregular shape providing two shoulders 74, 75 which respectively engage and hold the in-turned end 76 of the downwardly extending arm 71 of the T-lever in its normal and retracted positions, (Figs 1 and 2) respectively. As heretofore stated, the normal position is shown in Fig. 1. The engagement of arm 71 with shoulder 75 is shown in Figs. 2 and 3. Obviously when the latch 48 is tripped to release the lever 37 to 90 close the switch as hereinbefore described, the shoulder 49 slips by above the engaging shoulder of the latch; and in order to re-engage the latch and shoulder the former is raised by oscillating the T-lever slightly 95 about its pivot to the position shown in Fig. 2 in which the latch is again engaged with the shoulder of lever 37 without however moving lever 37 from the closed position.

The means for effecting the above described oscillation of the T-lever to again engage the latch and contact lever will now be described. On the end of shaft 9, which as described in the above-mentioned Rinsche patent is given a complete revolution by the 100 motor when the clutch is engaged, is a snail cam 53 and the latter engages a friction roll 54 upon a four-armed lever 55 which is pivoted upon the same post or stud 38 upon which levers 37 and 66 are pivoted; see 105 Figs. 1, 2 and 7. Spring 64 (see Fig. 5) connected to arm 55^a of the four-armed lever maintains the roller 54 in engagement with snail cam 53. Obviously, as the snail cam is revolved by the motor, lever 55 is oscillated about its pivot, the arm bearing the roller 54 being alternately depressed and permitted to rise under the impulse of the spring 64. The downwardly projecting arm 55^b of said lever carries a pin or stud 70 110 which projects forwardly and in advance of the edge of the aforementioned arm 71 of the T-lever, and when the roller 54 is depressed by the snail cam, stud 70 operates 115 against the edge of arm 71 forcing the latter 120 against the edge of arm 71 forcing the latter 125 against the edge of arm 71 forcing the latter 130

to the left (as seen in the Fig. 2) and into a position to be engaged by the shoulder 75 on latch 72. A spring 72^a connected at one end to a lug 72^b on said latch and at the other to a stationary stud 72^c lowers latch 72 into position for the shoulder 75 to engage the in-turned end 76 of arm 71 when the latter is moved to the left by the action of the snail cam, as above described. Obviously, so long as the parts remain in the position shown in Fig. 2 with the lower end of the arm 71 engaged by the shoulder 75 on latch 72, the switch remains closed even though the latch 48 is in engagement with the shoulder 49 upon lever 37. Provision is made, however, for the release of arm 71 by latch 72 and the restoration of the parts to normal condition when the finger-bar and consequently bar 27 by which latch 48 is operated remain idle, and the clutch open for a certain pre-determined period.

The construction as described up to this point is substantially the same as that disclosed in the Rinsche patent aforesaid, but the means for restoring the parts to normal position which will now be described is entirely different from the dash-pot controlled means of said patent. It comprises a thermostatic bar *a*, controlling the opening of the switch and surrounded by a heating coil 124 and a thermostat switch *b* governing the supply of current to the coil surrounding the thermostatic bar, the construction being such that as long as the machine is operated at pre-determined intervals, the thermostat will be maintained heated above the critical temperature, but as soon as the machine has been idle beyond the pre-determined period the thermostatic bar cools off and opens the contacts of the motor switch. For this purpose the thermostat bar comprising, as usual, two strips of metal 80, 81, of unequal coefficients of expansion is anchored at its upper end as by screws 82 to a stationary portion of the frame. To the lower end of the thermostat, as at 83, is pivoted a cam link 84 which, as the thermostat warps under the influence of heat, is carried back and forth from the position shown in Fig. 2 to that shown in Fig. 3, solid lines. The left-hand end of cam link 84 is up-turned as at 85 and connected by a spring 86 to a stud 47 so that said end 85 of the link is always urged upward. The upper edge of the cam link is formed at 88 with a hump for the purpose of rocking the rocker 89 as will presently appear. Said rocker is fulcrumed at 90 and carries at one end a stud 91 having an insulating covering which engages the movable contact 92 of the thermostat switch to close the circuit of the thermostat coil in a manner which will presently be described. For the present purpose it is sufficient to understand that when contact 92 is forced upward by the stud 91 the thermostat is heated and warped out of the position shown in Fig. 2 in the direction indicated in Fig. 3. Normally the rocker 89 is in the position shown in Fig. 1 and the tail 93 thereof is swung to the right as viewed in said figure, so that the V-shaped end 94 thereof is a trifle to the right of the apex 95 of the hump 88 on the cam link. In this normal position of the parts the outwardly turned end 96 of the right-hand arm of the rocker is in contact with the finger 97 of bell-crank lever 98 which is pivoted on stud 38, thus limiting the movement of said bell-crank lever under the impulse of its spring 99. (See Figs. 1 and 3.) Bell-crank 98 is swung to the left against the tension of its spring 99 when the machine is operated, the four-armed lever 55 being provided for this purpose with a stud 100 which engages the edge of said bell-crank lever when the four-armed lever is operated by the snail cam. The effect of the movement of the bell-crank lever to the left is to cause the cam surface 101 thereof to wipe along the outward turned end 96 of the rocker, depressing said end thereof and forcing the tail of the rocker to the left, so that the apex thereof passes the apex 95 of the hump 88 on the cam link. When this occurs the pull of spring 86 draws the cam link upward, completing the movement of the rocker so that the insulated stud 91 thereon engages the movable contact 92 and closes the circuit through the coil of the thermostat. (See Fig. 2.) This occurs during the initial movement of the four-armed lever 55 under the action of the snail cam and before said lever engages and moves the arm 71 of T-lever 66. The further movement of lever 55 under the influence of the cam as the highest point of the latter reaches the roller 105 brings the parts to the position shown in Fig. 2 in which the thermostat contacts remain closed and the lever 66 is locked in position by engagement of the arm 71 with the shoulder 75 of latch 72. The thermostat 100 now begins to heat up and to move the cam link 84 to the left, the hump 88 thereof wiping under the tail of the rocker until the apex of the hump passes the point of the tail of the rocker, when the cam surfaces of these parts under the tension of the spring 86 causes the rocker to swing back into the position which it is shown as occupying in Fig. 3, and in which the contacts of the thermostat are permitted to open. The thermostatic bar now begins to cool off and consequently the cam link moves toward the right; the arm 71 is, however, still held by the shoulder 75 of latch 72. If no other items are entered in the machine, as the thermostat continues to cool and approaches its ultimate position, latch 72 is raised to release the arm 71 and permit the lever 66 carrying the pawl or latch 48 to move counter-clockwise under the impulse of its spring 120 115 125 130

and, the latch 48 being in engagement with the shoulder 49 on the contact lever, to open the contact.

The release of the arm 71 from latch 72 is brought about by the following construction and operation. Said latch carries a trip lever 105 pivoted thereto near its free end by a pin and slot connection 106 so that said lever has not only a swinging 10 but a slight reciprocating movement relative to said latch. A spring 107 connected to a lug 108 on said trip and a stud 109 on the latch normally draws the trip to the left, as seen in Fig. 3. (See also Figs. 1 and 8.) Said 15 trip is also formed at its right-hand end with an inwardly extending finger 110 for a purpose which will appear. Upon the same stud 106 upon which the trip works is pivoted a trigger 112 formed with a shoulder 20 113 which is directly beneath the finger 110 when the trip is in its left-hand position, but is cleared by said finger when the trip is in its right-hand position. The left-hand end of the trip is formed with a lip 114 25 which projects into the notch in latch 72 in advance of the shoulder 75. The purpose of the trip and trigger is to release the arm 71 from the latch 72 at the proper time. The trip being drawn forward under the control 30 of its spring and the inwardly projecting end of arm 71 being against the shoulder 75 and beneath the lip on said trip, and the finger of the trip being immediately above the shoulder upon the trigger, when the latter 35 is drawn to the right, as seen in the several figures as the thermostat cools off and thereby swung about its pivot, the shoulder on the trigger engages the finger on the trip causing the latter to tilt downward at its 40 left end and to engage the inwardly projecting end of arm 71. This lifts the latch 72 in an obvious manner and releases the arm so that the lever 66 carrying the pawl 48 is restored to normal position and carries the 45 contact lever therewith, thus opening the circuit. As the arm 71 swings to the right it engages the downwardly extending edge 116 of the trip and carries the latter with it so that the finger on the trip then clears the 50 shoulder on the trigger.

As best seen in Figs. 1, 2 and 3, the lower end of the trigger is cam shaped and extends between a stud 117 and a boss 118 on a bracket 119 secured to the lower end of the 55 thermostatic bar. As the thermostat warps and the cam link is carried to the left the trigger is engaged by the stud 117 and swung to the left, taking the shoulder out of the way of the finger 110 upon the trip. As the 60 thermostat cools off and carries the cam link to the right the trigger is engaged by the boss 118 and swung about its pivot and the finger 110 being at this time directly above the shoulder of the trigger, the trip is tilted 65 as above described to release the latch from

the arm 71. Thus in the event that there is no succeeding operation of the adding machine while the thermostat is cooling off, the parts are in due time restored to normal with the circuit of the motor broken. This operation, though it has been described in connection with the description of the parts, may be briefly recited as follows: After the number which it is desired to enter in the machine has been set up, the finger-bar is 70 depressed as usual in motor-operated machines, raising the vertical bar 27 operating the clutch mechanism and tripping the latch 48. This permits the switch arm 37 to carry the knife into engagement with the contacts 80 34 and 35, thus closing the circuit through the motor and operating the latter and at the same time carrying the shoulder 49 above the cooperating shoulder upon the latch. The shaft 9 carrying the snail cam 53 then 85 revolves, the latter engaging the roller 54 upon the lever 55, rocking the latter about the stud 38 and causing the stud 100 to engage the bell-crank lever 98, swinging the latter about its fulcrum 38. This causes lever 98 90 to depress the right arm of the rocker swinging the tail of the hump to the left, past the apex of the hump of the cam link, when the upward tension on the latter completes the 95 rocking of the rocker so that it closes the circuit of the thermostat coil. The further movement of the lever 55 oscillates the T-lever clockwise to the position in which it is engaged by the shoulder 75 on latch 72 and the pawl 48 engages shoulder 49 on the contact lever. The thermostat warps to the left and if no more items are entered into the machine, as the apex of the hump on the cam lever passes the tail of the rocker, the tension 100 of the spring 86 lifting the cam link rocks 105 the rocker to open the thermostat circuit. During this movement to the left the trigger is swung and the trip also moves to the left so that the finger on the latter is over the shoulder on the former. After the thermostat begins to cool, however, the movement 110 of the bracket carried thereby to the right swings the trigger, tilting the trip, raising the latch 72 and thereby releasing the arm 71 so that the parts return to the normal position 115 shown in Fig. 1.

The previously described operation presupposes that no additional items are put in the machine after the first operation. If, however, additional items are put in the machine and the bar 27 depressed to enter the items in the machine, the clutch will be engaged and the snail will again revolve, oscillating the lever 55. If this occurs before the thermostat has cooled sufficiently to release the arm 71 from the shoulder 75, the oscillation of lever 55 has no effect on the latter. The bell-crank 98, however, is again operated and on its return the offset end 96 of lever 89 is caught on the shoulder 98 of 125 130

lever 98, so that the rocker 89 is not oscillated sufficiently to again close the thermostat circuit. This condition of the parts is represented in Fig. 6. As the thermostat 5 continues to cool off, however, ultimately the hump 88 wipes past the end of the tail of the rocker (which is prevented from swinging to the position shown in Fig. 1 by engagement with the bell-crank lever) and the upward 0 movement of the cam link under the influence of its spring again shifts the rocker to close the thermostat circuit. By reason of the last described feature of the construction whereby the thermostat circuit is not closed 5 throughout the full unwarping action of the thermostat a large amount of wear on the thermostat and its switch is avoided.

In order to insure proper adjustment of the parts in assembling, a lever 121 is pivoted 0 on the same stud 83 which carries the cam link, the forward end of said lever 121 being slotted to engage the stud 72 above mentioned. As shown in Fig. 1, the slot 122 engaging said stud limits the movement of the 5 parts connected to the lower end of the thermostat element to the right, and thus acts to position the parts with the apices of the hump of the cam link and nose of the rocker in the normal position shown in Fig. 0 1 when assembling.

I shall now describe the details of the thermostat and of the electric system by which it is heated, including the switch, heretofore referred to in a more general way as operated by the rocker 89, though it is to be understood that the specific construction shown, while satisfactory, need not be adopted in detail. The construction of the thermostatic element may best be understood in connection with Figs. 2, 3 and 4. The thermostatic element proper, *a*, may be formed of two strips of metals of unequal expansion, such as brass and steel, preferably cemented or soldered together as usual in such elements. In Fig. 4, which shows the thermostat on a very much enlarged scale, the strip is represented as reduced intermediate its ends at 123 to receive the heating coil 124, the latter being of insulated wire and covered by asbestos cord 124^a. The ends of the coil are connected to terminals 125, 126, extending into a block of insulating material 125^c, and secured to, but insulated from the tang 80 by rivets 127, 128 respectively. Terminal 125 is connected to post 30 by wire 125^a. A cover plate 129 is secured by the screws 82, previously described.

Referring to Fig. 10, which shows the wiring, 29^a, 29^b, represent connections from the source of current to the posts 30, 31. The motor circuit is included between the post 30 and post 33, the motor being shown diagrammatically at *f*. Knife 36, as heretofore described, closes the motor circuit when permitted to close. It also closes the heat-

ing circuit for the thermostat except for the thermostatic switch *b* which is subsequently closed by the operation of the time switch as heretofore described.

The details of the thermostat switch are 70 best shown in Figs. 9 and 11. As seen in said figures, a small casting 130 is formed with the hollow screw-threaded shank 131 which is adapted to receive a nut 132. An insulated conductor 133 extends through the 75 hollow of the bolt and is soldered or otherwise secured at its inner end to a spring plate 134 carrying the spring terminal 135. Said plate 134 and terminal 135 are insulated from the casting by a suitable insulating washer 136 and secured in position in a cutout portion of the casting by means of an insulated bolt 137. The movable contact member consists in a short sliding rod 92 extending into a transverse bore 139 in 80 the casting, said bore being enlarged at 140 to receive a spring 141 which engages a collar 142 on the rod and a washer 143, between which collar and washer the spring is compressed so that it normally forces the 85 contact outwardly. The entire construction is enclosed in an insulating casing 145 and insulated at 146 from the frame. Connection to the movable contact 92 is made by means of a wire 150 clamped between said 90 nut 132 and a washer 151 on the threaded shank of said casting.

In order to trip the latch 72 by hand when desired, it is formed with a heel 152 which extends into the path of a plunger 153 slidingly mounted in a bore 154 in the casing. A spring 155 compressed between the shoulder in the bore and the finger-piece 156 on the plunger normally maintains the latter in outer position, see Fig. 1. To lift 100 the latch it is only necessary to push the finger-piece of the plunger, but the latter is normally out of the way and does not interfere with the automatic operation of the device.

I claim:

1. In a time switch for controlling the circuit of a motor for operating adding machines and the like having a clutch for controlling the operation of the adding machine by the motor, manually operated means for tripping the switch to close the latter, means for opening the switch after an actuation of the clutch, and a thermostat controlling the last said means.

2. In a time switch for controlling the circuit of a motor for adding machines and the like having a clutch for controlling the operation of the adding machine by the motor, a shaft adapted to be revolved by the motor, 115 means for closing the switch, manipulative means for releasing the closing means, means operated by said shaft for opening the switch, and a thermostat controlling the 120 last said means.

3. In a time switch for controlling the circuit of a motor for adding machines and the like, a rotary shaft, means for closing the switch, a latch normally restraining 5 said means, manipulative means for releasing the latch, means operated by said shaft to open the switch, a thermostat controlling the last said means, electric heating means for said thermostat, and means operated by 10 said shaft for closing the circuit of said electric heating means.
4. In a time switch for controlling the circuit of a motor for adding machines and the like, a rotary shaft, a stationary contact, a movable contact, an arm carrying said movable contact, a spring for moving said arm to close the switch, a latch for holding the arm in open position against the pressure of said spring, manipulative 15 means for tripping the latch to release said arm, means operated by said shaft for re-engaging the latch and arm, a second latch for preventing the restoration of said contact arm to opened position, means for tripping said second latch, and a thermostat controlling the last said means.
5. In a time switch for controlling the circuit of a motor for adding machines and the like, a shaft adapted to be rotated by 20 the motor, a stationary contact, a movable contact, an arm carrying the latter, a spring moving said arm to close the switch, a latch for holding the arm in open position, manipulative means for tripping the latch, a lever carrying said latch, means operated by said shaft for shifting said lever to permit the latch to re-engage the contact-carrying arm, a second latch for holding said lever in shifted position, a thermostat, 25 means carried by the thermostat for tripping the second said latch, electric heating means for the thermostat, a switch in the circuit of said electric heating means, and means operated by said shaft for closing said switch.
6. In a time switch for controlling the circuit of a motor for adding machines and the like, a shaft adapted to be operated by the motor, a stationary and a movable contact, an arm carrying the latter, a spring for moving said arm to close the switch, a latch for holding the arm in open position, manipulative means to release the latch, a lever to which said latch is pivoted, means 30 for moving said lever from normal position to a position to permit said latch to re-engage the contact-carrying arm, means for restoring said lever to normal position, a latch for preventing the return of the lever to normal position, a thermostat, means operated by the thermostat for tripping the latter said latch to permit said lever to return to normal position, electric means for heating the thermostat, and a switch for 35 controlling said heating means.
7. In a time switch for controlling the circuit of a motor for adding machines and the like, a rotary shaft, a movable and a stationary contact, an arm carrying the latter, a spring for moving said arm to close the switch, a latch for holding the arm in open position, manipulative means for tripping the latch, a lever carrying the latch, means for normally holding the lever in position such that the latch when engaged with the 40 contact arm holds the latter in open position, a cam carried by said shaft, means operated by the cam for moving said lever to a position to re-engage the latch with the contact-carrying arm when the latter is in closed position, a latch for preventing the return of the lever to normal position, a thermostatic bar secured at one end to the framework of the switch, a trip lever for disengaging the second said latch from the 45 latch-carrying lever, a trigger engaged by the thermostat for operating the trip lever, a coil for heating the thermostat, a switch in the circuit of said coil, and means for opening and closing said switch.
8. In a time switch for controlling the circuit of a motor for adding machines and the like, a shaft, stationary and movable contacts, an arm carrying said movable contact, a spring for moving said arm to close the switch, a latch for holding the arm in open position, manipulative means for tripping the latch, to permit the arm to close the contact, a lever carrying the latch, a spring tending to move the lever to normal position, a cam carried by said shaft, means intermediate the cam and said lever to move the latter to position to permit the latch to re-engage the contact-carrying arm in closed 50 position, a latch to restrain the lever from return to normal position, a thermostat, means operated by the thermostat to trip the latch and permit the return of the lever to normal position, electric heating means for heating the thermostat, a switch in the circuit of said electric heating means, a rocker for closing the last said switch, means operated by said shaft for rocking said rocker.
9. In a time switch for controlling the circuit of a motor, a stationary and a movable contact, an arm 37 carrying the movable contact, a latch 48 for holding the arm in open position, manipulative means for tripping the latch, a lever 66 on which said latch is pivoted, a spring 67 tending to restore said lever to normal position, a shaft, a cam 53 carried by said shaft, a lever 55 rocked by said cam, means on the lever 55 for engaging lever 66 to swing the latter to a position in which the latch can re-engage arm 37, a latch 72 adapted to hold the lever 66 in the last said position, a trip on the last said latch adapted to rock and to disengage 60 said latch from the lever 66, a trigger 112 11
10. In a time switch for controlling the circuit of a motor, a stationary and a movable contact, an arm 37 carrying the movable contact, a latch 48 for holding the arm in open position, manipulative means for tripping the latch, a lever 66 on which said latch is pivoted, a spring 67 tending to restore said lever to normal position, a shaft, a cam 53 carried by said shaft, a lever 55 rocked by said cam, means on the lever 55 for engaging lever 66 to swing the latter to a position in which the latch can re-engage arm 37, a latch 72 adapted to hold the lever 66 in the last said position, a trip on the last said latch adapted to rock and to disengage 65 said latch from the lever 66, a trigger 112 12
11. In a time switch for controlling the circuit of a motor, a stationary and a movable contact, an arm 37 carrying the movable contact, a latch 48 for holding the arm in open position, manipulative means for tripping the latch, a lever 66 on which said latch is pivoted, a spring 67 tending to restore said lever to normal position, a shaft, a cam 53 carried by said shaft, a lever 55 rocked by said cam, means on the lever 55 for engaging lever 66 to swing the latter to a position in which the latch can re-engage arm 37, a latch 72 adapted to hold the lever 66 in the last said position, a trip on the last said latch adapted to rock and to disengage 70 said latch from the lever 66, a trigger 112 13

adapted to engage and rock the trip, a thermostat bar secured at one end to the framework and having means to engage and operate the trigger, electric heating means for the thermostat, a switch in the circuit of said electric heating means, and means operated by said cam 53 for closing the switch of said electric heating means.

10. In a time switch for controlling the circuit of a motor for adding machines and the like, a stationary and a movable contact, an arm carrying said movable contact, a spring for moving said arm to close the switch, manipulative means for permitting 15 the arm to close the contacts, means including a thermostat for governing the opening of the contacts, a coil surrounding the thermostat, a circuit for said coil including a source of current and a switch, means set 20 in motion by said manipulative means for closing the last said switch.

11. In a time switch for controlling the circuit of a motor for adding machines, a stationary and a movable contact, an arm 25 37 carrying the latter, a spring impelling said arm to close the switch, a latch 48 for engaging the arm and holding the switch open, a lever 66 carrying the latch, a spring tending to move the lever 66 to normal 30 position, a cam 53 on said shaft, a lever 55 operated by the cam, a stud on the lever 55 to engage lever 66 and bring the latter to a position to permit latch 48 to re-engage arm 37 when in closed position, a second latch for 35 maintaining lever 66 in the last said position, a thermostat, electric means for heating the thermostat, a circuit for said electric means, a switch for controlling said circuit, means controlled by said thermostat 40 for closing and opening the last said switch.

12. In a device of the class described, a switch having a stationary and a movable contact, an arm carrying the movable contact, means for swinging the arm in a direction to close the switch, means adapted 45 to be operated by the motor controlled by the switch for opening the switch, a thermostat, electric means for heating the thermostat, a circuit therefor controlled by said 50 switch, and means controlled by the thermostat for preventing the operation of the switch-opening means for a predetermined period.

13. In a device of the class described, a 55 switch controlling a motor circuit, a catch for holding the switch open, a device for tripping the catch to close the switch, a cam for re-setting the switch in open position, a thermostat, electric means for heating the thermostat, a circuit therefor controlled by said 60 switch, and means controlled by the thermostat for preventing the opera-

tion of the switch-opening means for a predetermined period.

14. In a device of the class described, a 65 switch for controlling the circuit of a motor, a catch normally holding the switch in open position, manipulative means for releasing the catch and permitting the switch to close, a cam adapted to be operated by 70 the motor, a lever operated by the cam for resetting the switch in open position, a thermostatic element, a latch controlled thereby for holding the lever inoperative, electric heating means for heating the latter, the 75 circuit of said electric heating means controlled by the switch, a second switch in the circuit of the electric heating means, means operated by said cam for closing the last said switch.

15. In a time switch for opening the circuit of a motor operated adding machine and the like, including a movable contact for closing the motor circuit, a catch normally holding said contact in open position, manipulative means to trip the catch and permit the said contact to close the switch, means for moving said contact to closed position, means for restoring the contact to open position, a latch for preventing the return of the contact to open position, a thermostat, an electric heating means therefor, a circuit for said means, a switch for said circuit, means for closing the last said switch controlled by said thermostat.

16. A time switch for opening the circuit of a motor-operated adding machine or the like, including a movable contact for closing the motor circuit, an arm carrying said contact, a catch normally engaging the arm and holding the contact in open position and arranged to be tripped by the manipulative means to release the arm, a spring tending to move the arm to close the switch, a cam adapted to be driven by said shaft, a second lever having an arm extending into the path of said cam to be swung thereby, means on the second lever to engage the first lever and swing it to a position in which the catch thereon may engage the contact carrying arm when the latter is in closed position, a spring tending to restore the catch carrying lever to normal position, a latch adapted to engage the last said lever when the latter is moved from normal position and prevent its return to normal position, means for releasing the lever from the latch comprising a thermostat, electric heating means for the thermostat, and a circuit for the electric heating means controlled by said switch.

THEODORE S. BINDSCHEDLER.
